CLAIM

The ornamental design for a sauce container, as shown and described.

DESCRIPTION

FIG. 1 is a front perspective view of a sauce container, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view showing the sauce container in an open state.

The broken lines in the drawings illustrate the portions of the sauce container that form no part of the claimed design.
